PAPER CLIP

Arthur J. Lewis, Stratford, Conn., assignor to
 The Autoyre Company, Watertown, Conn., a
 corporation of Connecticut

Application December 24, 1934, Serial No. 759,023

7 Claims. (Cl. 24—261)

This invention relates to new and useful improvements in clips, and has particular relation to clips for securing together a plurality of sheets of paper or the like.

5 An object of the invention is to provide a clip of the kind indicated and which is capable of maintaining a good grip on a small number of sheets of thin paper and which will also, without causing a set in the wire of the clip, securely grip 10 together a large number of sheets of paper.

Other objects and advantages will become apparent from a consideration of the following detailed description taken in connection with the accompanying drawing wherein satisfactory embodiments of the invention are shown. However, it will be understood that the invention is not limited to the details disclosed but includes all such variations and modifications as fall within the spirit of the invention and the scope of the 20 appended claims.

In the drawing:

Fig. 1 is an elevational view of the improved clip;

25 Fig. 2 is an edge view looking from the lower side of Fig. 1;

Fig. 3 is a view similar to Fig. 1 but showing the clip as used in securing together sheets of paper;

30 Fig. 4 is a sectional view taken substantially along the plane of the line 4—4 of Fig. 3;

Fig. 5 is a sectional view taken substantially along the plane of the line 5—5 of Fig. 3;

Fig. 6 is a view similar to Fig. 1 but showing a slightly modified construction; and

35 Fig. 7 is an edge view looking from the right in Fig. 6.

Referring in detail to the drawing and at first particularly to Figs. 1 through 5 the improved clip is shown as formed from a single length of 40 wire and comprising a generally triangular shaped frame 10 and a tongue 11 within the frame. The frame 10 includes a closed rounded lower end or nose 12 and diverging sides 13 and 14. At the upper ends of the sides 13 and 14 the wire is carried inwardly providing arms 15 and 16 extending toward one another and connected with the frame sides 13 and 14 respectively by the bends 17.

The arms 15 and 16 are of the same or substantially the same length and by bends 18 are 50 connected with parallel depending members 19 and 20 which members comprise portions of the tongue 11 and extend in the direction of the rounded lower end 12 of the frame. Each of the depending tongue members 19 and 20 at its lower 55 end carries a small loop 21 and the loops of the respective members comprise upwardly directed extensions 22 connected with the respective members by bends 23 which are preferably rounded as shown so that each loop has a closed rounded 60 lower end. The two end portions of the single

length of wire from which the clip is formed are at the upper ends of the extensions 22, and these end portions designated 24 and 25 respectively are bent inwardly and extend toward one another and toward the depending members 19 and 20 and are connected with the extensions 22 by corners or bends 26. The portions 22 are preferably closely adjacent and substantially parallel to side portions 13 and 14 to give a good grip on thin paper or a small number of sheets, as well as give a good grip on a larger stack of papers as indicated at 8 and 9 in Fig. 5.

When applying the clip the tongue 11 may be engaged by a thumb and pressed out of the frame 15 to either side thereof or when the rounded lower end 12 of the frame is placed against the upper side of one of the sheets which are to be connected together, and by moving the clip onto the sheets or moving the sheets into the clip the clip 20 will be positioned with its frame at one side of the sheets and its tongue at the other side thereof as shown in Figs. 3, 4 and 5 wherein the clip is shown in place on two sheets of paper or other material A. With the clip in place the arms 15 and 16 extend in a direction diagonally across the edges of the connected sheets. The bends 17 connecting the arms with the sides 13 and 14 of the frame act more or less as fulcrums when the tongue is pressed to either side of the frame.

30 Therefore, as the tongue is pressed out of the frame the depending members 19 and 20 of the tongue rock or turn outwardly relative to one another, with the result that the small loops 21 at the lower ends of such members are turned to direct the extensions 22 toward the frame as suggested in Fig. 5, and to particularly bring their bends or shoulders 26 against the sheets A being secure. Additionally, as the tongue is forced through the frame the lower end of the tongue 40 moves the greatest distance and the upper portions 24 and 25, and particularly the corner portions 26 of its small loops, are tilted inwardly and tend to dig into or form a sharp bend in the sheets as shown in Fig. 4 at 26a to increase resistance to removal of the clip from the papers.

45 It will be noted that the extensions 22 forming portions of the small loops 21, are arranged relatively close to the sides 13 and 14 of the frame 10, and it will therefore be apparent that the clip 50 will securely grip even a small number of thin sheets of paper. The arms 15 and 16 are relatively long and the clip may, therefore, be used on a relatively thick stack of papers without causing a set in the wire.

55 The thicker the pad of paper to which the clip is applied the further the tongue will be forced out of the frame and the more the tongue will be inclined to cause the upper portions 24 and 25, and particularly the shoulders 26 of its small loops to 60

dig into or form a sharp bend in the paper as shown in Fig. 4, and thus increase the grip on the paper and increase its resistance to removal of the clip therefrom. Also, the thicker pad of paper results in additional fulcruming of the arms 15 and 16 about the bends 17, so that the depending members 19 and 20 of the tongue are rocked or turned to a greater degree relatively so as to cant or turn the small loops inwardly as suggested in Fig. 5 to force their portions 22, and particularly their shoulders or bends 26, against the paper. Since the tongue can be bent out of the frame in either direction should it be set by bending to one side it may be used to make a good grip by bending it in the opposite direction.

In Figs. 6 and 7 the shape of the frame is slightly modified but the structure of the tongue is the same as that previously described, and the tongue 20 has the same reference characters applied thereto as in Figs. 1 through 5. In the modified construction the frame is generally designated 27 and includes sides 28 and 29 the lower portions 30 and 31 of which are inclined and connected by a rounded lower end 32. The sides of the frame are bent at 33 and their upper portions 34 and 35 extend substantially parallel whereby the clip is somewhat rectangular. The portions 30 and 31 correspond to the lower portions of the sides 13 and 14 of the first form and have the same relation to the tongue and the portions 22 thereof. Arms 36 and 37 are connected with the upper portion of the frame sides by bends 38 corresponding with the bends 17 of Fig. 1 and said arms extend 35 toward one another and by the bends 39, corresponding with the bends 18 of Fig. 1, are connected with the depending members 19 and 20 of the tongue 11.

This modified construction has the same advantages as the structure of Fig. 1 insofar that the clip may be easily applied, that the tongue may be displaced to either side of the frame, and that the small loops of the tongue, and particularly the bends or corners 26 of said loops will tend to dig into or form sharp bends in the papers as shown in Figs. 4 and 5. However, since the arms 36 and 37 of the modified construction are shorter than the arms 15 and 16 of Fig. 1 the tongue of the modified construction can not be forced laterally out of the frame as great a distance without causing a set in the wire as can that of the first form. Therefore, the construction of Figs. 6 and 7 for a similar size of clip is not adapted for the securing together of the sheets of such a thick pad as is the construction of Figs. 1 through 5.

Having thus set forth the nature of my invention, what I claim is:

1. A clip formed from a length of wire comprising a frame having a base and sides connected in a lower rounded end, and an inner tongue comprising two centrally located depending members each including a lower rounded end and an outer upwardly directed extension closely adjacent and substantially parallel with the adjacent side member and having its end bent and directed toward its depending member to provide a corner adjacent a side of the frame spaced a material distance from the base so as to be movable out of the plane of the frame.

2. A clip formed from a length of wire comprising a frame including a base and sides connected at their lower ends, an inner tongue com-

prising two centrally located depending members, and a substantially closed loop at the outer side of and carried by the lower end portion of each of said members and said loops being spaced a material distance from the base so as to be movable out of the plane of the frame.

3. A clip formed from a length of wire comprising a frame including sides connected at their lower ends, an inner tongue comprising two centrally located depending members, a substantially closed loop at the outer side of and carried by the lower end portion of each of said members, arms connecting the upper ends of said members with the sides of the frame, and said frame, members and loops arranged in the same plane with the loops spaced a material distance from the arms so as to be movable out of the plane of the frame.

4. A clip comprising a wire bent to provide a rounded lower end and upwardly and outwardly inclined sides, said wire bent at the upper ends of the sides to provide inturned arms extending toward one another, said wire bent downwardly at the inner ends of said arms to provide parallel members extending toward said rounded end, and the ends of the wire at the lower ends of said parallel members extending outwardly and upwardly substantially parallel to the sides for a short distance and then bent in toward the downwardly extending members at a material distance from said arms so as to grip papers in the clip at a distance from the edges thereof.

5. A clip formed from a length of wire comprising a frame including a rounded lower end and upwardly and outwardly inclined sides, arms extending toward one another from the upper ends of said sides, a pair of independent members depending one from the inner end of each of said arms, and a loop at the outer side of and carried by the lower end portion of each of said members and spaced a material distance from the arms so as to be movable out of the plane of the frame.

6. A clip formed from a length of wire comprising a frame including a rounded lower end and upwardly and outwardly inclined sides, a tongue within the frame and comprising a pair of parallel independent depending members extending toward said rounded end, and a loop at the outer side of the lower end portion of each of said members and each comprising an upwardly directed extension close to and substantially parallel with a side and an inwardly directed portion at the upper end of the extension and extending toward the depending members, said inwardly directed portion being spaced a material distance from the base of the frame so as to grip papers in the clip at a distance from their edges.

7. A clip comprising a wire bent to provide a lower end and upwardly extending sides, said wire bent at the upper ends of the sides to provide inturned arms extending toward one another, said wire bent downwardly at the inner ends of said arms to provide substantially parallel members extending toward said rounded end, and the ends of the wire at the lower ends of said members extending outwardly and upwardly for a short distance and then bent in toward the downwardly extending members and spaced a material distance from said arms so as to grip papers in the clip at a distance from their edges.

ARTHUR J. LEWIS.
